(57) **CLAIM**

The ornamental design for a kitchen ventilation hood, as shown and described.

DESCRIPTION

This application is being filed together with two other kitchen ventilation hood design applications by the same inventor on this same date. The other applications are 29/127,124 and 29/127,125.

The Shade kitchen ventilation hood is based upon the simple design of a matchbook. When the retractable and distinctive canopy is closed its lines are clean and unobtrusive.

FIG. 1 is an upper right front perspective view in closed position;

FIG. 2 is an enlarged front elevational view in closed position;

FIG. 3 is an enlarged left side elevational view; the right side is a mirror image thereof;

FIG. 4 is an enlarged rear elevational view in closed position;

FIG. 5 is an enlarged top plan view in closed position;

FIG. 6 is an enlarged bottom plan view in closed position;

FIG. 7 is an upper front right perspective view in opened condition;

FIG. 8 is an enlarged front elevational view in opened condition;

FIG. 9 is an enlarged left side elevational view; the right side is a mirror image thereof;

FIG. 10 is an enlarged rear elevational view in opened condition;

FIG. 11 is an enlarged top plan view in opened condition; and,

FIG. 12 is a bottom plan view in opened condition.

The broken line showing of environmental structure is for illustrative purposes only and forms no part of the claimed design.
